(57) **CLAIM**

The ornamental design for a side chair, substantially as shown and described.

DESCRIPTION

FIG. 1 is a front perspective view of a side chair in accordance with the present invention;

FIG. 2 is a rear perspective view thereof;

FIG. 3 is a front view thereof;

FIG. 4 is a rear view thereof;

FIG. 5 is a left side view thereof;

FIG. 6 is a right side view thereof;

FIG. 7 is a top view thereof; and,

FIG. 8 is a bottom view thereof.

Any shading or hatching are not features of the design and are merely utilized to illustrate surface contours of the design in the drawings.
